UNITED STATES PATENT OFFICE.

GEORGE B. McCACKEN AND SAMUEL HAMER, OF WILLIMANTIC, CONN.

SPINDLE AND BEARING THEREFOR.

SPECIFICATION forming part of Letters Patent No. 269,438, dated December 19, 1832.

Application filed May 13, 1882. (No model.)

To all whom it may concern:

Be it known that we, GEORGE B. McCACKEN and SAMUEL HAMER, of Willimantic, in the county of Windham and State of Connecticut, have invented a new and useful Improvement in Spindles and Bearings Therefor, of which the following is a full, clear, and exact description.

Our invention relates to that class of spindles in which the bobbin is held steady at the top by a short spindle and turned by a whirl placed on a central stud; and it consists in the construction, arrangement, and combination of the parts of the spindle, whereby the bobbin is made to run easy, steady, and true, the bearings properly oiled without the oil retarding the motion of the spindle or soiling the bobbin, the oil used over and over again, and the supply of oil in the reservoir not agitated by the motion of the spindle, and also whereby the parts of the spindle may be easily taken apart for cleaning and the wearing parts replaced with ease and small expense, all as hereinafter described.

Reference is to be had to the accompanying drawings, forming part of this specification, in which similar letters of reference indicate corresponding parts in all the figures.

Figure 1 is an elevation of our new and improved spindle and a portion of the rail with the bobbin removed. Fig. 2 is an elevation of the bobbin. Fig. 3 is a central vertical section, part in elevation, of our invention. Fig. 4 is an elevation of the bushing in which the short spindle B is held. Fig. 5 is an inverted plan of the lower end of the said bushing, showing the perforations therein. Fig. 6 is an elevation of the bushing D, forming the upper bearing of the sleeve E. Fig. 7 is a cross-sectional view of the bushing D, showing the grooves therein. Fig. 8 is a partial sectional elevation of said sleeve E; and Fig. 9 is an elevation of the tube placed in the lower oil-cup, F, for preventing agitation of the oil in the cup from the rapid revolution of the downward extension of the whirl G of the spindle.

A represents the iron base of the spindle, which is cast so as to form the oil-reservoir F, in which the oil for lubricating the lower bearings of the spindle is placed. The bottom of this reservoir is formed with the annular de-

pression or channel f' for the retention of any sediment or gritty deposits that may be in the oil, and the base A is adapted to be secured to the rail H in the ordinary manner.

Firmly screwed into the base A is the stud C, which is made small enough to be slightly elastic, but not so elastic that it will be liable to be deflected by the pull of the band which turns whirl G. The object of making this stud slender is to so condition the spindle that it will adjust itself to any unequal distribution of the load, the same as a packed bolster will do.

The sleeve E is placed upon the stud C and turns with the whirl G, and surrounding the sleeve and the stud is the short tube J, which reaches to the bottom of the reservoir F and protects the supply of oil in the main part of the reservoir from being agitated by the rapid revolution of the said sleeve E, and the spindle from being retarded by the oil in the reservoir.

The lower edge of the tube J is by preference formed with the notches jj, through which the oil passes from the main body of the reservoir to and in contact with the sleeve and stud. The sleeve E has secured in it at its lower end the bushing A', which fits and turns upon the stud C and forms the lower bearing for the sleeve, and formed upon or secured to the outside of the sleeve are the collars b and b', the latter being at the upper end of the sleeve, as shown. These collars fit snugly the interior of the hollow and slightly-tapered upward extension d of the whirl G, so that the sleeve E is made fast to the whirl, and is thus caused to turn with it.

The lower end of the bushing A' of the sleeve E rests upon the bottom of the oil-reservoir F, and is beveled off, as shown at i i, for reducing the friction and to facilitate the inflow of oil from the reservoir to its bearings upon the stud C. The bushing D is fitted snugly into the sleeve E a suitable distance above the bushing A', and forms the upper bearing for the sleeve E. This bushing D is formed with the oil passages or gutters e e upon its outside, as shown clearly in Fig. 7.

When the spindle is in use the rapid revolution of the sleeve E will cause the oil to be drawn up between the stud C and the inner wall of the sleeve from the bushing A', and to work between the stud C and the inner wall of the bushing D, into the upper end of

the sleeve E above the bushing D, and above the collar b', where quite a quantity will be maintained, which will always insure the thorough lubrication of the bearing between the bushing D and the stud C.

5 Above the bushing D the sleeve E is by preference formed upon the inside, with the spiral groove or thread e, which will tend to carry or force the oil back through the gutters e e of the bushing D and down to the reservoir F, so that the oil will be used over and over again.

The stud O may, if found necessary, be formed with a spiral groove or thread for assisting the oil to rise from the reservoir for lubricating the bushing D. By this means it will be seen that it will be impossible for the oil to clog up the oil-passages, so as to materially interfere with perfect lubrication, as the gutters in the bushing D, in connection with the spiral grooves in the sleeve E, furnish several sources of supply, all of which are not likely to get clogged at the same time. The upper end of the stud C is headed, as shown at f, which is centrally socketed, as shown at 25 f' in Fig. 3, and in this socket the lower end of the short spindle B takes its bearing.

To the upper end of the stud C is secured the shell K, the lower end of which forms a stop for the upper end of the sleeve E to strike 30 against when doffing. In the upper end of the shell K is screwed the bushing L, which is formed with the downward extension L', which incloses the greater part of the short spindle B, as shown in Fig. 3. At the lower end of the 35 downward extension L' of the bushing is formed the collar l, extending across the space o, between the shell K and the outside of the extension L', which forms an oil-reservoir for holding the supply of oil for lubricating the 40 upper bearings of the spindle, and this reservoir o communicates with the lower oil-reservoir p through the perforations g g, made through the collar l of the extension L'.

The reservoirs o and p are filled with oil 45 through the passage h and side passages, i' i', made in the upper end of the short spindle B, and the vertical passages e' e', made in the bushing L. (Shown in Fig. 3.) The downward extension L' forms a tube, through which the oil is 50 drawn by the rapid revolution of the spindle from the lower oil-reservoir p up to the bearing of the short spindle B in the bushing L. This raising of the oil may be aided, if desired, by forming a spiral groove or thread in the inside of 55 the downward extension L'. The collar l fits the shell K and prevents the oil in the reservoir o from being agitated by the revolution of the spindle. Reservoirs o and p are practically one, both being kept full of oil, the collar 60 l serving to check the violent motion of the oil, which might otherwise be driven up away from the step f' by the centrifugal force of collar m on the spindle B. The oil, after passing up the spindle B and sleeve L' for oiling the 65 spindle, passes into the passages e' e' in the bushing back to the reservoirs o and p, to be

used over again. The hole t in the upper end of the bushing L serves for a vent, and as a place to insert a tool to serve as a lever or wrench for unscrewing the bushing. t' is a 70 similar hole or passage through the lower end of the shell K and through the stud C for receiving a tool for unscrewing the stud from the casting A.

The upward extension d of the whirl G is, as 75 above mentioned, made slightly tapering or conical, so that the bobbin N will fit tightly upon it. The upper end of the bobbin fits upon the upper end of the short spindle B, by which it is steadied, and the short spindle revolves 80 with the bobbin. By this means it will be seen that the weight of metal that revolves with the bobbin is reduced to the minimum, thus requiring less power to revolve the spindle, and obviating, to a great extent, the vibration which the spindle would otherwise have. The passage h through the short spindle B, while serving for an oil-duct, also materially 85 lightens the spindle without impairing its strength.

Upon the lower end of the short spindle is driven the collar m, which prevents the spindle from being raised out of its step in the head f when doffing. In filling, through the passage h of the short spindle, the reservoirs o 90 and p with oil, should the oil happen to overflow through the holes t, it will pass down the outside of the shell K, into the upper end of the upward extension d of the whirl, and from thence, through the gutters e in the bushing D, 100 down inside of the sleeve E into the lower reservoir F, and not in any manner soil the bobbin.

By this construction and method of oiling 105 it will be seen that the oiling is positive and sure, that the reservoirs will hold enough oil to run a long time without refilling, and that the reservoirs are so arranged that the motion of the spindle will not be retarded by the supply 110 of the oil in the reservoir, nor the supply agitated by the motion of the spindle. It will also be seen that, the bobbin being held only at top and bottom, and the weight of metal revolving therewith being very small, the spindle 115 will run very light, steady, and true; that the size of the bearings does not exceed the usual 120 size of the best spindles; that the side pull of the band is done away with, and that in case of wear the bushings A', D, and L can be 125 readily and easily replaced at a small cost and very little delay, and the spindle can also be easily taken apart for cleaning and repairs.

Having thus fully described our invention, what we claim as new, and desire to secure by Letters Patent, is—

1. The combination, with the fixed stud C and the short spindle B, stepped to revolve therein, of the shell K, secured upon said stud, and the bushing L, secured to shell K and adapted to serve as a bearing to spindle B, as 130 shown and described.

2. The combination, with the fixed stud C,

provided with head *f*, forming the bottom of reservoir *p*, of the shell *K*, forming its side walls, and the downward extension *L'*, provided with the collar *l*, forming its top, as shown and described.

3. The combination, with the shell *K*, of the bushing *L*, provided with the downward extension *L'* and collar *l*, as shown and described.

10 4. The combination, with the stud *C*, provided with the head *f* and socket *f'*, the shell *K*, the bushing *L*, provided with the extension *L'*, passages *e'*, and collar *l*, having passages *g* through it, and the reservoirs *o p*, of the spindle *B*, provided with the oil-passage *h i*, as shown and described.

5. The combination, with the bushing *L* and its reduced downward extension *L'*, having passages *e'*, of the spindle *B*, provided with 20 the passages *h i*, communicating with the said passages *e'*, the latter opening through the shoulder of bushing *L*, outside of its extension *L'*, as shown and described.

6. The combination, with the stud *C*, the 25 shell *K*, secured to the upper end thereof, and the bushing *L*, provided with the downward extension *L'*, of the spindle *B*, stepped in stud *C* and provided with the collar *m*, as shown and described.

30 7. The stud *C* and the shell *K*, secured to

the upper end of the same, in combination with the spindle *B*, the bushing *L*, provided with downward extension *L'*, and collar *l*, forming the oil-reservoir *p*, as shown and described.

8. The sleeve *E*, provided with flanges or 35 collars *b b'*, in combination with the tapering upward extension *d*, fitting on said collars, and the whirl *G*, of which said extension is a part, as shown and described.

9. The whirl *G*, provided with extension *d*, 40 sleeve *E*, stud *C*, and bushings *D A*, adapted to rotate thereon, in combination with the shell *K*, the bushing *L*, and the spindle *B*, stepped in the end of stud *C*, as shown and described.

10. The whirl *G*, having the upward extension *d*, and the sleeve *E*, secured therein, in combination with the stud *C*, spindle *B*, shell *K*, the bushing *L*, having the downward extension *L'*, and the reservoirs *o p*, and *F*, as shown and described. 45

11. The bushing *D*, formed with the gutters *e e*, in combination with the stud *C* and sleeve *E*, substantially as described. 50
